SUTURE PACKAGE

Sidney B. Bradshaw, Chicago, Ill., assignor to
Armour and Company, Chicago, Ill., a corpora-
tion of Illinois

Application September 24, 1949, Serial No. 117,530

4 Claims. (Cl. 206—63.3)

1

My invention relates to an improved easily opened suture container for the storage and shipment of sterilized surgical sutures.

Requirements of surgical asepsis demand that suture materials be transported and stored in sealed germ-free containers. In addition, however, the containers must be easily opened to afford access to the suture material without contamination and without tending to break or weaken any portions of the suture. Moreover, the container must protect the suture from damage during transportation or due to undesirable sharp bends or knots incident to packing.

Heretofore it has been common practice to package surgical sutures in sealed glass tubes containing alcohol or like antiseptic carrier. These packages have secured asepsis at the expense of other desirable characteristics. In particular, the tubes can be opened only by breaking the glass, an operation that is not only hazardous to the nurse or other person opening the tube but, in addition, complicates withdrawal of the suture material since sharp edges naturally surround the broken end of the tube.

The difficulties inherent in opening a glass suture tube are increased by the necessity of maintaining asepsis. Rubber gloves must be worn and all the objects with which the tube comes in contact must be completely sanitary. The natural tendency of users of the tubes is to sacrifice sterility and take the risk of possible damage to the suture material to facilitate opening the tube, a common practice being to encase the tube within a towel and strike the towel with a heavy object to break the tube.

In accordance with the present invention an easily opened sterile suture container is defined by a pair of thin flexible metal disks having mating skirt portions. A gasket is sandwiched between the disks to define a vacuum tight seal. The suture is retained adjacent the skirts by a suitable carrier. After the suture, carrier, and mating disks are assembled and the space filled with a suitable antiseptic carrier fluid, the unit is placed in a vacuum chamber which withdraws all air and causes the mating disks to flex inwardly. Vacuum seal holds this condition of the carrier until use of the suture. When a suture is to be used, the disks are slightly twisted relative to each other or pierced to break the vacuum and the suture is then easily removed.

It is therefore a general object of the present invention to provide an easily opened suture container capable of carrying sterile sutures in a sanitary manner.

2

Another object of this invention is to provide an improved easily opened suture container that protects the suture against physical damage.

5 A further object of the present invention is to provide an improved receptacle for the suture container of the present invention.

The novel features which I believe to be characteristic of my invention are set forth with particularity in the appended claims. My invention itself, however, both as to its organization and method of operation may best be understood by reference to the following description taken in connection with the accompanying drawings, in which:

15 Figure 1 is an axial cross-sectional view with parts in elevation showing a dispensing and shipping receptacle with a plurality of suture containers of the present invention;

20 Figure 2 is a cross-sectional view through axis 2—2, Figure 1;

Figure 3 is an axial cross-sectional view of the suture container of the present invention before vacuum is drawn;

25 Figure 4 is a view like Figure 3 but showing the container after vacuum is drawn;

Figure 5 is an exploded view of the container; and,

Figure 6 is a top plan view showing the suture carrier with a suture contained therein.

30 As best seen in Figures 3 to 5, the container of the present invention includes a pair of disk members 10 and 12 having mating skirts 10a and 12a. An annular gasket 14 of rubber or like flexible material is interposed between the two disk members to effect a vacuum tight seal. The skirt portion 10a of member 10 is wrapped about itself or beaded to define a smooth lip 10b capable of bearing against the gasket 14 without tending to puncture the same.

35 The disks 10 and 12 are made of metal, such as 28 gauge aluminum sheets. Alternatively plastic or other material may be employed. The disk 10 has a circular outwardly extending rib 10c to increase its flexibility. Flexibility of disk 12 is increased by the depressed circular portion 12b.

40 The suture S is wound in a circular coil and rides adjacent the skirt portion 10 of the inner member 10. The suture is carried in this position by the carrier 16. As shown in Figure 5, this carrier has four outwardly extending arms 16a, each bent over the suture S at its end as shown at 16b. The suture is thus confined in a circular coil adjacent the skirt portion 10a of the member 10.

When the containers are packed, the suture S is first placed on the carrier 16 and the ends bent over to confine the suture in a circular coil. The carrier and suture are then encased in the member 10 and sterilized as a unit. Member 10 is then filled with sterile alcohol or similar antiseptic carrier fluid and gasket 14 and member 12, both previously sterilized, are then fitted in position.

In the foregoing condition, the container is placed in a vacuum chamber where air is withdrawn. This causes some of the liquid carrier to escape and flexes the members 10 and 12 from the condition of Figure 3 to that of Figure 4 where they may even touch at their centers. At this time the suture container is free of air and, in addition, contains only a rather small amount of the antiseptic fluid.

In the foregoing condition, the container is a perfectly sanitary suture container. The pressure of air on the outside causes the edge 10b of the member 10 to press hard against the gasket 14 and effect a tight seal. This seal I have denominated a vacuum seal since it is sealed by the presence of a low pressure within the container.

To open the container it is merely necessary to twist members 10 and 12 relative to each other to cause a slight breakage of the seal and release the vacuum. The members 10 and 12 flex easily to destroy the vacuum and permit members 10 and 12 to be separated.

Alternatively, the vacuum may be broken by piercing member 10 or member 12. This may be accomplished by forceps having a sharp prong capable of piercing one of these members.

Preferably the material of the suture container has a high degree of flexibility so that it cups substantially under air pressure as shown in Figure 4. The container then indicates whether it has been opened or leaks by the fact that the members 10 and 12 expand from the flexed condition of Figure 4 to the unflexed condition of Figure 3. The user can instantly observe whether the suture is sterile and ready for use by noting that the container is still sealed by vacuum.

Since it is only necessary to break the vacuum seal of the container to open it, there is no danger to the person using the container and, moreover, there is no tendency to damage the suture as the container is opened. In fact, when the seal is broken and the member 12 is lifted off, the suture is laid out in a convenient coil in condition suitable for use.

Moreover, the suture S is confined by carrier 16 to the space adjacent skirt 10a of member 10. This skirt effectively protects the suture from physical damage, either due to the pressure forcing the members 10 and 12 together or due to external blows.

Figures 1 and 2 show a convenient receptacle to ship and dispense the suture containers of the present invention while keeping the outer surface of the containers sterile. As indicated, this receptacle is defined by an elongated cup 18 having a threaded portion 18a adjacent its upper lip. The cup is slightly greater in diameter than the suture containers to receive the lift rod 20. At its bottom end this rod defines a loop 20a to engage and lift the suture containers and at its top end it is bent to define the horizontal hook 20b.

For shipment, the receptacle 18 receives a threaded cap (not shown) to retain its contents.

After shipment this cap is replaced by the cap 22 which is sterilized prior to being placed on receptacle 18. This cap merely rests on the upper lip of the receptacle and has a handle 22a to facilitate removal. A vertical hook 22b depends from and links with the hook 20b of lift rod 20 so that the lift rod is raised when the cap 22 is lifted. The hooks 20b and 22b are placed in the linked condition by resting cap 22 over the receptacle with the hook 22b aligned with the cap 20c of hook 20b and then rotating the cap to link the hooks as shown.

The receptacle 18 contains sterile alcohol or some like antiseptic fluid during shipment and storage. When it is desired to remove a container, the top 22 is lifted, thus automatically raising the top container above the fluid level. The top container may then be removed for use as described above.

While I have shown and described a specific embodiment of my invention, it will of course be understood that I do not wish to be limited thereto and that by the appended claims I intend to cover all modifications and alternative constructions falling within the true spirit and scope of my invention.

What I claim as new and desire to secure by Letters Patent of the United States is:

1. An easily opened container containing a sterilized surgical suture, comprising a pair of manually twistable plates having inwardly turned skirt portions, one of said plates being slightly larger than the other of said plates and the skirt portions of the larger of said plates receiving the skirt portions of the smaller of said plates, thereby providing a small chamber between said plates, a gasket disposed about the inner peripheral portion of the larger of said plates so that the lower edge of the skirt of the smaller of said plates bears on said gasket, a sterile surgical suture coiled within said chamber so as to leave the central region of said chamber open, the central portions of said plates being flexed towards each other under the force of atmospheric pressure so that the lower edge of the skirt of the smaller of said plates sealably engages said gasket, whereby said sealable engagement can be broken by merely grasping said container between the hands and applying a twisting force to change the contours of said plates.
2. An easily opened container containing a sterilized surgical suture, comprising a pair of manually twistable disks having inwardly turned annular skirt portions, one of said disks being of a slightly smaller diameter than the other of said disks, the skirt portion of the smaller of said disks being received inside of the skirt portion of the larger of said disks, thereby providing a small circular chamber between said disks, a gasket disposed about the inner peripheral portion of the larger of said disks so that the lower edge of the skirt of the smaller of said disks bears on said gasket, a sterile surgical suture coiled within said chamber so as to leave the central region of said chamber open, the central portions of said disks being flexed towards each other under the force of atmospheric pressure so that the lower edge of the skirt of the smaller of said disks is held in air-tight engagement with said gasket, said container being manually twistable to change the contours of said disks, whereby said air-tight seal can be broken and said container opened by manually twisting said disks to change their relative alignment.
3. An easily opened container containing a

sterilized surgical suture, comprising a pair of manually twistable disks having inwardly turned annular skirt portions, one of said disks being of a slightly greater diameter than the other of said disks, the skirt portion of the smaller of said disks being received inside of the skirt portion of the larger of said disks, thereby providing a small circular chamber between said disk, the lower edge of the skirt of the smaller of said disks being rounded to provide an arcuate annular contact surface, an annular gasket disposed about the inner peripheral portion of the larger of said disks beneath said contact edge of the skirt of the smaller of said disks so that said contact edge seats on said gasket, the larger of said disks having a depressed circular portion inwardly of said gasket extending toward the smaller of said disks, a sterile surgical suture coiled within said chamber so as to leave the central region of said chamber open, and an antiseptic carrying fluid within said chamber and substantially covering said suture, the central portions of said disks being flexed towards each other under force of atmospheric pressure so that the contact edge of the smaller skirt portion is held in air-tight engagement with said gasket and said disks are contiguous at their centers, said container being manually twistable

10

to change the alignment of said disks relative to each other, whereby said air-tight seal can be broken by merely grasping said container between the hands and applying a twisting force.

5 4. The suture container of claim 2 in which there is also provided a suture carrier adapted to fit snugly within the innermost of said disks and having bent over portions to confine the suture to the space adjacent the skirt portion thereof.
